UNITED STATES PATENT OFFICE.

GUSTAVE E. FRANQUIST, OF NEW BRUNSWICK, NEW JERSEY.

DISTANCE-ROD FOR AUTOMOBILES.

1,094,140.

Specification of Letters Patent. Patented Apr. 21, 1914.

Application filed May 8, 1913. Serial No. 766,268.

To all whom it may concern:

Be it known that I, GUSTAVE E. FRANQUIST, a citizen of the United States, residing at New Brunswick, in the county of 5 Middlesex and State of New Jersey, have invented certain new and useful Improvements in Distance-Rods for Automobiles, of which the following is a full, clear, and exact description.

10 This invention relates to self-propelled vehicles of that particular class in which power is transmitted from a driving shaft to the driven axle, through chains and sprocket-wheels.

15 The object of the invention is to provide a construction of distance-rod between the power-shaft and axle which will not be affected by abnormal relative movements of the shaft and axle, due to strains encountered 20 mainly through inaccuracies of road surface over which the vehicle travels.

A further object is to provide a distance-rod between the power-shaft and axle which will permit of the removal of the axle from 25 the vehicle without the complete removal of the distance-rod.

30 A further object of the invention is the provision of convenient means for adjusting the tension of the drive-chain, and a still further object is the provision of a housing 35 for the chain and a mounting thereof which will, like the distance-rod, be relieved of strains, due to relative movements of the power-shaft and axle.

35 With these objects in view, the invention consists: first, of a distance-rod connecting the power-shaft and axle together, with a connection between the power-shaft and the distance-rod which permits the latter to 40 twist or rotate freely in a direction transverse to the axis of the shaft, whereby there will be no tendency to communicate such motion to the shaft itself; second, in making the distance-rod in two parts which are 45 readily separable from each other; third, in locating the chain-adjusting devices outside of the chain housing and at a point where they are readily accessible; and, fourth, in mounting the chain housing upon 50 the distance rod solely so that it will freely partake of such motions as are imparted to the rod.

In the accompanying drawings, Figure 1 is a plan of the distance-rod and its connections, with the upper half of the chain housing removed and portions of the mechanism

in section; Fig. 2 is a vertical section through the chain housing, the power shaft and axle showing the distance rod in side elevation; Fig. 3 is a section on the line 60 3-3 of Fig. 1, but on a considerably larger scale.

Referring to the drawings by letter, 1 indicates the side frame of the chassis of a self-propelled vehicle; 2 indicates the 65 driven axle, and 3 the driving shaft to which power is communicated in any well known way from a suitable motor on the vehicle. The axle 2 is supposed to be connected with the body of the vehicle through the usual 70 springs (not shown), a seat for one of the springs being shown at 4 which is secured to the axle by means of the bolts 5. The power-shaft 3 is rigidly supported upon one side of the frame of the chassis by means 75 of the bracket 6 and bolts 7 and the bracket 8 and bolts 9, and on the other side by the same or any other suitable means. From the bracket 6 extends a sleeve around the shaft which terminates at its outer end in a ball- 80 cup 10 for ball bearings on which the shaft runs. The shaft is fitted with a ring 11 which, together with a ring on the inside of the cup, forms the ball-race for the balls 12. Fixed upon the end of the shaft is the 85 hub 13 which carries the sprocket pinion 14. The sleeve upon which the cup 10 is formed, is embraced by a collar 15 from which projects forward a cylindrical bracket 16 through which passes a vertical pin 17, the 90 ends of which project beyond the ends of the bracket and pass through the arms of a yoke 18, which arms embrace the opposite ends of the cylindrical bracket. This yoke has a tail-piece 19 extending forward and 95 having its extremity threaded. The outer ends of the pin 17 and the outer adjacent surfaces of the yoke 18 are machined off to form cylindrical surfaces having a common axis which passes horizontally through the 100 center of the shaft 3 in a fore-and-aft direction.

The distance-rod is composed of two sections indicated respectively by 20 and 21. The section 20 is essentially an open rectangular frame comprising two horizontal sides 105 22 and 23, connected together by a vertical cross-piece 24. The shaft 3 passes through this frame and the frame is in the same plane with the yoke 18 and bracket 16, the outer curved surfaces of the yoke bearing against the inner face of the frame parts 22

and 23, these faces being curved throughout their length to correspond with the curvature on the faces of the yoke so that the frame may be adjusted longitudinally and 5 meanwhile slide upon the end surfaces of the yoke. At the same time, it will be seen that by reason of the corresponding cylindrical surfaces between the yoke and the frame, the frame may be twisted or rotated 10 on an axis at right angles to the axis of shaft 3 without imparting any strain to the yoke 18, bracket 16, or shaft 3. The frame section 20 of the distance rod is provided with two lugs 25, 25, for the reception of 15 bolts 26, which also pass through similar lugs 27 on the section 21 of the distance-rod for the purpose of rigidly securing the two sections together and forming them into one single structure. These bolts are prevented 20 from turning when their nuts are screwed on, by a straight edge 28 which rests upon an outer flat surface on the frame as seen in Fig. 3. The frame section 20 is provided with a tubular extension 20' leading from 25 the center of the cross-piece 24, and the tail-piece 19 of the yoke 18 extends through and beyond this tubular extension and is adjustable longitudinally with respect thereto by means of a nut 29 in the form of a sleeve 30 externally and internally threaded. The interior surface of the tubular extension is threaded with a pitch opposite that on the tail-piece and the nut is correspondingly threaded to engage both of these threads, so 35 that when the nut is rotated the tube and tail-piece will move in opposite directions with respect to each other, or, more properly it should be stated, that the tail-piece 19 which is connected to the rigidly mounted 40 shaft 3, will remain stationary while the tubular extension, which is connected to the distance rod, will be moved longitudinally with respect thereto in a direction corresponding to the direction in which the nut 45 is turned. The end of the tubular extension is slotted, as at 30, so that it may be contracted to lock the nut, by means of the split cap 31 which is passed over the end of the tube and contracted by means of a bolt 32. 50 To adjust the nut, it is of course necessary to first remove this cap, after which it is replaced to lock the adjustment and protect the parts from injury.

55 The section 21 of the distance rod is in the form of a plate with a reinforcing web 33. It is provided with an opening near its rear end through which the driven axle 34 passes. The axle is provided with a sleeve 35 having a cylindrical bracket 36 60 through which a pin passes into and through ears 37 on the rod, thus forming a hinge-joint between the rod and axle, permitting the shaft to swing horizontally to a slight degree without straining the distance rod.

65 38 indicates a drum which is supposed to

be rigidly attached to one of the vehicle wheels running upon the axle 34. This drum is provided with sprocket-teeth 39 in the same plane with the sprocket-pinion 14, and power is supposed to be communicated 70 from the pinion to the drum by means of a sprocket-chain passing over these two sprocket-wheels. The bosses 40 and 41 are merely bearings for studs used in the brake rigging and have no special significance in 75 my invention. Grease cups 42 are also shown but have no significance. The inner side of section 20 of the distance rod is closed by a plate 43 to prevent the entrance of dirt and this plate is provided with elongated openings permitting shaft 3 to pass through it and permit of the adjustments 80 which will be hereinafter referred to.

The housing for the chain is indicated by 85 44 and consists of sheet or cast metal made in two parts divided longitudinally along the center, the interior side wall of the housing being cut away to fit the contour of the distance-rod, the edges of this cut-away part fitting in the grooves around the edges 90 of the distance-rod as indicated by the dotted lines 45. As a further support for the housing, the distance-rod is provided with a web-like bracket 46 against which the abutting edges of the two halves of the housing 95 rest, grooves 47 being provided in the bracket to receive the edges of the housing. The outer wall of the housing is provided with a large circular opening, permitting it to receive the drum 38 and with a somewhat 100 smaller opening in which is fitted a cup 48 covering the end of the shaft 3. The two parts of the housing are bolted together at several points indicated by 49, and in this manner it will be seen that the housing is 105 sustained entirely by and upon the distance-rod, so that any motions which are imparted to the rod are freely partaken of by the housing and no strain is brought upon the latter. The provision of the sleeve 15 on shaft 3 and the sleeve 35 on axle 34, permits either the sleeve or the axle to move 110 vertically without straining the distance rod, and hinge-joints 36 and 37 between the axle and the distance rod as well as the 115 similar joint between the shaft 3 and the distance rod, permit the axle and shaft to assume a slightly non-parallel relation without straining the distance-rod. Whenever 120 one or both wheels on the axle 34 pass over irregularities in the road, the axle has a vertical movement which tends to twist the distance rod, and this twisting is compensated for by the opposite end of the rod rotating upon the curved ends of the yoke 18, 125 so that no strain is placed upon the rod. When it is necessary to remove the axle 34 from the vehicle, this may be done without dis-assembling the forward end of the distance-rod and its associated parts, by re- 130

moving the bolts 26 which then permit the section 21 of the distance-rod to be moved away with the axle, the chain-housing of course having first been entirely removed.

5 This is an important feature of my invention since to remove the entire distance rod would require considerable time and difficulty. In order to adjust the tension of the chain which passes over sprocket-wheels 14 and 39, the axle is caused to approach or recede from the shaft 3, and this is done by applying a wrench to the nut 29 and giving it the required number of turns to effect the adjustment. In thus turning the nut, 10 the whole distance-rod, together with the rear axle, is drawn forward or pushed rearward, while the frame 22, 23, meanwhile slides longitudinally upon the curved faces of the yoke 18.

20 Having described my invention, I claim:—

1. In a vehicle, the combination of two shafts, a distance rod connecting them together, one end of the rod having an opening through which one of the shafts passes, longitudinal arc shaped bearing surfaces on the walls of said openings and a bracket attached to said shaft and having corresponding arc-shaped bearings in engagement with those on the rod and means for moving the rod to cause the bracket to travel lengthwise thereof.

2. In a vehicle, the combination of a distance-rod, a shaft, a bracket, longitudinal arc-shaped guides on the rod engaged by said bracket and means for sliding the bracket along said guides.

25

30

35

3. In a vehicle, the combination of a distance-rod, a shaft, a bracket, longitudinal arc-shaped guides on the rod engaged by said bracket and a threaded member co-operating with the rod and the bracket whereby the bracket may be caused to slide along said guides. 40

4. In a vehicle, the combination of a distance-rod, an axle and a shaft connected thereby, a threaded member carried by the rod, a threaded member carried by the shaft and a rotary threaded member engaging with the threads of the other two members whereby the relative positions of the rod and shaft may be adjusted by manipulating said rotary member. 45

5. In a vehicle, the combination of a distance rod and a shaft arranged at an angle to each other, said rod having a tubular portion internally threaded and the shaft carrying a tail piece externally threaded and passing through said tubular portion, and an internally and externally threaded nut engaging the threads on both the tubular 50 portion and the tail piece. 55

6. In a vehicle, the combination of a distance-rod and a chain housing, the latter having an opening in its side occupied by the former and the housing being solely supported by the rod. 60

In witness whereof, I subscribe my signature, in presence of two witnesses.

GUSTAVE E. FRANQUIST.
